UNITED STATES PATENT OFFICE.

AMANDA M. PALMER, OF LOS ANGELES, CALIFORNIA.

PESSARY.

1,160,953.

Specification of Letters Patent. Patented Nov. 16, 1915.

Application filed June 19, 1915. Serial No. 35,129.

To all whom it may concern:

Be it known that I, AMANDA M. PALMER, a citizen of the United States, residing at Los Angeles, in the county of Los Angeles and State of California, have invented certain new and useful Improvements in Pessaries; and I do hereby declare the following to be a full, clear, and exact description of the invention, such as will enable others skilled in the art to which it appertains to make and use the same.

This invention relates to pessaries, and the primary object of the invention is to provide an appliance, for therapeutic purposes in the treatment of affliction or diseases, peculiar to female generative organs, such as prolapsus uteri or the like, constructed of soft pliable material, such as elastic rubber, which will embody curative properties without causing irritation of the organs or uncomfortable feeling when the patient is in a sitting posture or moves about.

Another object of this invention is to provide a pneumatic pessary adaptable for inflation after insertion into a vagina, which includes a collapsible outer wall having its edges secured in airtight connection to an inner substantially rigid tube, forming an air space which is inflated after insertion of the pessary into the vagina for properly supporting the uterus; further to coil a fine spring about the inner tube for holding it in place and to permit of movement or bending of the tube upon movement of the body of the patient.

A still further object of this invention is to provide a cross bar which extends diametrically across the outer end of the inner tube for facilitating the removal of the pessary from a vagina; and also to mount an air controlling valve in the outer end of the pessary for facilitating the inflation of the same.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate

like and corresponding parts throughout the several views, and in which:

Figure 1 is a side elevation of the pessary inflated, Fig. 2 is a side elevation of the pessary in a collapsed form, Fig. 3 is a perspective view of the pessary, showing the outer end of the same, Fig. 4 is a view of the pessary, showing a part of the outer collapsible wall removed, Fig. 5 is a longitudinal section through the pessary, and Fig. 6 is a side elevation of the inner substantially rigid tube.

Referring more particularly to the drawings, 1 designates the inner tube of the pessary, which is constructed of soft rubber, or analogous material, and has a ring 2 formed about its upper end and positioned at an incline with respect to the longitudinal axis of the tube. A ring 3 is formed about the base of the tube 1. An outer collapsible wall 4, which is constructed of soft elastic rubber, is secured to the rings 2 and 3, in airtight connection therewith, and forms a space 5 between the outer surface of the tube 1 and the inner surface of the collapsible wall 4, which may be inflated.

The ring 3 has an air valve 6 of any suitable construction, secured thereto, which communicates with the interior of the ring, and the space 4, for inflating the pessary, when desired. A cross bar 7 is secured to the ring 3 and extends diametrically across the same, being provided for facilitating the removal of the pessary from a vagina, the cross bar being provided for engagement with a person's forefinger for removing the pessary. The tube 1 has a spring 8 coiled about the outer surface of the same, for holding it substantially rigid, and for permitting of movement or bending of the pessary upon movement of the body of the patient upon which it is used.

In the employment of the improved pessary, the same is inserted into a vagina, when in a collapsed position, as shown in Fig. 2 of the drawings, after which any suitable type of air pump is connected to the valve 6, and the pessary is inflated to the desired size. The pessary may be inflated to any desired size, as is necessary for properly performing its function.

In reducing the invention to practice, certain minor features of construction, com-

bination and arrangement of parts may necessitate alteration, to which the patentee is entitled, provided such alterations are comprehended within the scope of what is 5 claimed.

What is claimed is:—

1. In a pessary, a tube constructed of soft flexible material having one end cut at an incline to the central longitudinal axis of 10 the tube, a spiral spring coiled about said tube, and a protecting wall surrounding said spring and tube.

2. In a pessary, an inner tube, a spring coiled about said tube, an outer collapsible 15 wall secured to said tube for forming an inflatable pessary, and an air valve communicating within said inflatable portion of said pessary.

3. In a pessary, an inner tube, rings 20 formed upon the ends of said tube, a collapsible wall secured to said rings and extending about said tube for forming an air space between the tube and said wall.

4. In a pessary, an inner tube constructed 25 of soft flexible material, rings formed upon the ends of said tube, a collapsible wall secured to said rings and extending about said tube for forming an air space between the tube and wall, a spiral spring coiled about 30 said tube.

5. In a pessary, an inner tube constructed of soft flexible material, rings formed upon the ends of said tube, a collapsible wall secured to said rings and extending about said 35 tube for forming an air space between the tube and the wall, a spiral spring coiled about said tube, and a cross bar extending diametrically across the outer tube.

40 6. In a pessary, a tube having one end cut at an incline to the central longitudinal axis of the tube, a spring coiled about said tube, an outer collapsible wall secured to said tube

for forming an inflatable pessary, an air valve communicating with the inflatable portion of said pessary. 45

7. In a pessary, an inner tube constructed of soft flexible material, rings formed upon the ends of said tube, the ring formed upon one end of said tube being disposed at an 50 incline to the central longitudinal axis of the tube, a collapsible wall secured to said rings and extending about said tube for forming an air space between the tube and wall, and a spiral spring coiled about said 55 tube.

8. In a pessary, an inner tube constructed of soft flexible material, rings formed upon the ends of said tube, the ring formed upon one end of said tube being disposed at an 60 incline to the central longitudinal axis of the tube, a collapsible wall secured to said rings and extending about said tube for forming an air space between the tube and the wall, a spiral spring coiled about said 65 tube, an air valve communicating with the inflatable portion of the pessary.

9. In a pessary, an inner tube constructed of soft flexible material, rings formed upon the ends of said tube, the ring formed upon one end of said tube being disposed at an 70 incline to the central longitudinal axis of the tube, a collapsible wall secured to said rings and extending about said tube for forming an air space between the tube and the wall, a spiral spring coiled about said 75 tube, an air valve communicating with the inflatable portion of the pessary, and a cross bar extending diametrically across the outer end of said tube. 80

In testimony whereof I affix my signature in presence of two witnesses.

AMANDA M. PALMER.
